DESIGN.

No. 29,270.

Patented Aug. 23, 1898.

F. S. PEARSON.

YOKE FOR RAILWAY CONDUITS.

(Application filed July 14, 1898.)

UNITED STATES PATENT OFFICE.

FRED S. PEARSON, OF BOSTON, MASSACHUSETTS.

DESIGN FOR A YOKE FOR RAILWAY-CONDUITS.

SPECIFICATION forming part of Design No. 29,270, dated August 23, 1898.

Application filed July 14, 1898. Serial No. 685,961. Term of patent 7 years.

To all whom it may concern:

Be it known that I, FRED S. PEARSON, a citizen of the United States, and a resident of Boston, in the county of Suffolk and State 5 of Massachusetts, have invented a certain new Design for Yokes for Railway-Conduits, of which the following is a specification.

The accompanying drawing illustrates a yoke formed according to my design. 10 The central portion *a* of the yoke is hollow, having the bottom *b*, sides *c c*, ends *d d* and open at the top. In the sides *c c* are elliptical openings *e e*, reaching from the top to the bottom or base *f* of the yoke. On the out-

side of the central portion of the yoke, on each 15 end *d d*, are projections *g g*, having the upper flat surfaces *h h* and lower flanges *i i*.

The leading feature of my design consists of the hollow central portion *a* with the bottom *b*, sides *c c*, and ends *d d*, as shown in 20 the drawing.

I claim—

The design for a yoke for railway-conduits as substantially herein shown and described.

F. S. PEARSON.
